(57) **CLAIM**

The ornamental design for a stuffed toy as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a stuffed toy showing my new design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The dashed broken lines define the bounds of the claimed design and form no part thereof, and the heavily lightened portions within the dashed broken lines form no part of the claimed design.
